UNITED STATES PATENT OFFICE.

ADOLPH C. RECKER, OF OAKVILLE, CONNECTICUT, ASSIGNOR TO WATERBURY MFG. CO.,
OF WATERBURY, CONNECTICUT, A CORPORATION.

DESIGN FOR A CASE FOR VACUUM-BOTTLES.

50,589.

Specification for Design.

Patented Apr. 10, 1917.

Application filed February 13, 1917. Serial No. 148,451. Term of patent 14 years.

To all whom it may concern:

Be it known that I, ADOLPH C. RECKER, a citizen of the United States, residing at Oakville, in the county of Litchfield and State of Connecticut, have invented a new, original, and ornamental Design for a Case for Vacuum-Bottles, of which the following is a specification, reference being had to the accompanying drawing, forming part thereof.

The figure is a side view of a case for vacuum bottles, showing my new design.

I claim:

The ornamental design for a case for vacuum bottles, as shown.

ADOLPH C. RECKER.

Witnesses:

J. S. NEAGLE,
VERA C. Goss.
